US00D772402S

(12) **United States Design Patent** (10) **Patent No.:** **US D772,402 S**
(45) **Date of Patent:** **** Nov. 22, 2016**

(54) **ABSORBENT ARTICLE**

5,932,039 A 8/1999 Popp et al.
5,951,536 A 9/1999 Osborn, III et al.
5,961,505 A 10/1999 Coe et al.

(71) Applicant: **Kimberly-Clark Worldwide, Inc.**,
Neenah, WI (US)

(Continued)

(72) Inventors: **JuHyung Lee**, Yongin-si (KR); **SungSu Kim**, Yongin-si (KR); **Moonyoung Cho**, Yongin-si (KR); **SeoYeon Son**, Seongnam-si (KR); **HyungWoo Park**, Suwon-si (KR)

FOREIGN PATENT DOCUMENTS

EP 0 764 433 A1 3/1997
EP 0 923 921 A1 6/1999

(Continued)

(73) Assignee: **Kimberly-Clark Worldwide, Inc.**,
Neenah, WI (US)

(**) Term: **15 Years**

(21) Appl. No.: **29/528,635**

(22) Filed: **May 29, 2015**

(51) LOC (10) Cl. **24-04**

(52) U.S. Cl.

USPC **D24/124**

(58) **Field of Classification Search**

USPC D24/124-126; 604/347, 348, 358-361,
604/378, 380, 385.01, 385.201, 385.22,
604/385.24, 385.25

See application file for complete search history.

Primary Examiner — Garth Rademaker

Assistant Examiner — Samantha Q Lawrence

(74) *Attorney, Agent, or Firm* — Kimberly-Clark Worldwide, Inc.

(57) **CLAIM**

We claim the ornamental design for an absorbent article, as shown and described.

DESCRIPTION

FIG. 1 is a top view of an absorbent article.

FIG. 2 is a first side view of the absorbent article of FIG. 1.

FIG. 3 is a back view of the absorbent article of FIG. 1.

FIG. 4 is a second side view of the absorbent article of FIG. 1.

FIG. 5 is a first end view of the absorbent article of FIG. 1; and,

FIG. 6 is a second end view of the absorbent article of FIG. 1.

The broken lines shown in FIGS. 2 and 4-6 illustrate portions of the absorbent article that form no part of the claimed design.

1 Claim, 2 Drawing Sheets
